UNITED STATES PATENT OFFICE.

CHARLES R. BEALL, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY VEHICLE GOVERNING APPARATUS.

Application filed July 1, 1924. Serial No. 723,528.

To all whom it may concern:

Be it known that I, CHARLES R. BEALL, a citizen of the United States, residing at Swissvale, in the county of Allegheny and State of Pennsylvania, have invented certain new and useful Improvements in Railway Vehicle Governing Apparatus, of which the following is a specification.

My invention relates to railway vehicle governing apparatus, that is, to apparatus carried by a vehicle for governing the speed thereof.

I will describe two forms of apparatus embodying my invention and will then point out the novel features thereof in claims.

In the accompanying drawing, Fig. 1 is a diagrammatic view showing one form of apparatus embodying my invention, and Fig. 2 is a view showing a modification of a portion of the apparatus shown in Fig. 1, and also embodying my invention.

Similar reference characters refer to similar parts in each of the views.

Referring first to Fig. 1, the reference character V designates an axle and a pair of wheels of a railway vehicle on which is mounted all the rest of the apparatus shown in this view. This also actuates a centrifugal device C, comprising a collar 2 fixed to the axle, a collar 3 mounted to slide on the axle, and two weights 4 and 4^a for sliding the collar 3 in opposition to the action of a spring 5 in accordance with the speed of rotation of the axle. The centrifugal device C operates a controlling member 6 carrying a controlling contact 7 and checking contact 8. The controlling contact 7 coacts with a series of fixed contact members A, whereas the checking contact 8 coacts with a series of fixed contact members D. The operation is such that when the vehicle is at rest the contacts 7 and 8 engage with the lowest of the fixed contact members A and D, as shown in the drawing, whereas when the vehicle is running at the highest speed of which it is capable, these contacts engage with the uppermost of the fixed members A and D. For intermediate speeds the contacts 7 and 8 engage with intermediate ones of the fixed contact members A and D.

The reference character 9 designates a controlled member carrying a controlled contact 10 and a checking contact 11. The con-

trolled contact 10 coacts with a series of fixed contact members B, whereas the checking contact 11 coacts with fixed contact members E. The controlled member 9 is operated in the manner hereinafter explained.

Two impedances, here shown as resistances R' and R² are connected in multiple across a source of current F, which source, as here shown, is a battery. The circuit for resistance R' is from battery F, through wires 15 and 16, resistance R', and wires 17 and 18 to battery F. The circuit for resistance R² is from battery F, through wires 15, 16 and 19 resistance R², and wires 20, 21 and 18, to battery F. The fixed contact members A are electrically connected by means of wires 56 with points of different electrical potential on the resistance R', whereas the fixed contact members B are electrically connected by wires 57 with points of different electrical potential on resistance R². It will be seen, therefore, that as the controlling member 6 moves upwardly, the controlling contact 7 will be progressively connected with points of different potential on resistance R', and that as the controlled member 9 moves upwardly the controlled contact 10 will be progressively connected with points of different potential on resistance R².

The controlled member 9 is provided with a central vertical aperture which is adapted to coact with a screw 12 and this screw is in turn operated by an electric motor M. The field winding 13 of motor M is constantly supplied with current from battery F, the circuit being from this battery, through wires 15 and 22, field winding 13, and wires 21 and 18 to battery F. One terminal of the armature 14 of motor M is connected with the controlling contact 7 by wire 23, and the other terminal of this armature is connected with the controlled contact 10 by wire 24.

The operation of the parts of the apparatus thus far described, is as follows: When the controlling contact 7 and the controlled contact 10 coact with points on the resistances R' and R² having the same electrical potential no current will flow in armature 14 of motor M, so that this motor will be at rest. When the controlling contact 7 moves

into engagement with a point on resistance R' having a different potential from the point of resistance R^2 with which the controlled contact 10 is in engagement, current 5 will flow through the armature 14 of motor M in one direction or the other according as the potential of contact 7 is higher or lower than the potential of contact 10, and the motor and screw 12 are so arranged that 10 the motor will then be operated in the proper direction to move the controlled contact 10 into engagement with a point on resistance R^2 having the same potential as the point on resistance R' with which the controlling contact 7 is in engagement. It will thus be seen that the controlled member 15 9 will occupy different positions at different speeds of the wheels and axle V, or that, in other words, different speeds of the vehicle 20 will be reproduced by different positions of the controlled member 9.

The reference character G designates a relay which is controlled by traffic conditions in advance in such manner that under clear 25 traffic conditions the contact finger 26 is swung to the left to engage with a fixed contact 27, under caution traffic conditions the contact finger 26 is swung to the right to engage with fixed contact 28, and under 30 dangerous traffic conditions the contact finger 26 occupies an intermediate position wherein it engages with a fixed contact member 29. The means for controlling the relay G forms no part of my invention, and, consequently, such means are not shown in the 35 drawing.

The controlled member 9 operates a contact bar 34 which coacts with three fixed contacts 35, 36 and 37. These fixed contacts are of different lengths so that when 40 the speed of the vehicle is between zero and a given low speed, such as 15 miles per hour, the contact bar 34 is in engagement with all three of the fixed contacts 35, 36 and 45 37; when the speed of the vehicle rises above 15 miles per hour the contact bar 34 moves away from contact 37; when the speed of the vehicle rises above an intermediate value, such as 35 miles per hour, the contact bar 50 34 passes out of engagement with contact 36; and when the speed is above a high value, such as 60 miles per hour, the contact bar 34 passes out of engagement with contact 35.

55 The reference character H designates apparatus for controlling the brakes of the vehicle. As here shown, this apparatus comprises a pipe 30 provided with a valve 31 which is controlled by the armature 33 of an electromagnet 32. As long as magnet 32 is energized the valve 31 is held closed and the brakes are not affected, but when magnet 32 becomes de-energized, thereby releasing its armature 33 and allowing valve 31 to 60 open, the consequent reduction of pressure

in the pipe 30 operates through any suitable apparatus to cause an automatic application of the brakes.

Assuming that the vehicle is traveling under proceed traffic conditions, so that contact 26-27 of relay G is closed, the magnet 32 is provided with a circuit which passes from a battery 38, through wire 39, contact 26-27, wire 40, contact member 35, contact bar 34, wire 43, checking contact 11, 70 contact member E, wire 25, contact member D, checking contact 8, wire 44, magnet 32, and wire 58 to battery 38. This circuit will be closed provided the speed of the train does not exceed 65 miles per 80 hour. If the speed does exceed this value, the circuit will be opened at contact 35-34, whereupon magnet 32 will release valve 31 and thereby cause an automatic application of the brakes. If the train is traveling 85 under caution traffic conditions the circuit for magnet 32 will be the same as before except that it will include contact 26-28, wire 41 and contact member 36. Under this condition the train may proceed at 90 speeds below 35 miles per hour, but if the speed exceeds this value, the circuit for magnet 32 will be opened at contact 34-36, and an automatic application of the brakes will occur. If the vehicle is traveling under 95 dangerous traffic conditions, the circuit for magnet 32 will be the same as before except that it will include contact 26-29 of relay G, wire 42 and contact member 37. The vehicle may then proceed at speeds below 15 miles per hour, but if the speed exceeds this value, the circuit for magnet 32 100 will be opened at contact 34-37, and an automatic application of the brakes will occur. 105

It will be noted that the circuit for magnet 32 always includes the checking contacts 8 and 11 and a pair of fixed contacts D and E. The purpose of these elements is to check the synchronism of the controlled member 9 and the controlling member 6. As long as these two members move in synchronism the checking contacts 8 and 11 are electrically connected by a pair of fixed contacts D and E and the wire 25 connecting these contacts, but if member 9 does not respond to a movement of member 6 then the checking contacts 8 and 11 will not be electrically connected through contacts D and E and wire 25, whereupon the circuit for magnet 32 will be opened and the brakes will be applied. 110 115 120

In the arrangement here shown, the magnet 32 is made slow-releasing in character, because when the controlling member 6 125 moves from one position to another the circuit for this magnet will be opened between checking contacts 8 and 11 until the controlled member has responded by a corresponding movement. The slow-acting charac- 130

teristic of magnet 32 is such as to bridge this time interval and so to prevent an automatic application of the brakes when a change occurs in the position of the controlling member 6.

It is possible that difficulty may be encountered in making the motor M sufficiently sensitive to provide for synchronism in the positions of members 9 and 6, and in that event the apparatus shown in Fig. 2 may be used. Referring to Fig. 2, the motor M is controlled by a relay K, the winding of which is connected with the contacts 7 and 10 by wires 23 and 24, respectively. Relay K is of the polarized type, so that it responds to the polarity of the current supplied to its winding. The field winding 13 of motor M is constantly supplied with current from battery F, through wires 15, 47 and 48, field winding 13, and wires 49, 21 and 18 to battery F. When contacts 7 and 10 engage with points of the same potential on resistances R' and R², relay K is de-energized, and the armature 14 of the motor M is then de-energized so that the motor is at rest. When the controlling contact 7 is shifted to such position that the potential of contacts 7 and 10 are different, relay K will be energized in one direction or the other according as the potential of contact 7 is above or below the potential of contact 10. Assuming that the energization is in such direction as to swing the contact fingers 45 and 46 to the left, armature 14 of motor M is then energized by a circuit which passes from battery F, through wires 15, 47 and 50, contact 45-59, wire 51, armature 14, wire 52, contact 46-60, and wires 53 and 18 to battery F. Motor M then rotates in the proper direction to shift member 9 to such position that the potentials of contacts 7 and 10 are the same. If relay K is energized in the opposite direction, the circuit for armature 14 is from battery F, through wires 15, 47 and 50, contact 45-61, wires 54 and 52, armature 14, wires 51 and 55, contact 46-62, and wires 53 and 18 to battery F. Current then flows through the armature 14 in the opposite direction so that motor M is rotated in the opposite direction and serves to shift the member 9 to such position that the potentials of contacts 7 and 10 are the same.

One important feature of my invention is the fact that the centrifugal device C is used only to move the controlling member 6, so that this centrifugal device may be made small and light, with the result that it may have a high degree of sensitivity.

In both Figs. 1 and 2, the electromotive forces supplied to resistances R' and R² are direct current electromotive forces, but it should be pointed out that this particular feature is not essential.

Although I have herein shown and described only two forms of apparatus em-

bodying my invention, it is understood that various changes and modifications may be made therein within the scope of the appended claims without departing from the spirit and scope of my invention.

Having thus described my invention, what I claim is:

1. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, means operating when said two contacts do not engage with points of equal potential on said resistances to move the controlled contact to such position that the two contacts do engage with points of equal potential on the two resistances, and governing apparatus on the vehicle controlled at least in part by the position of said controlled contact.

2. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, a winding connected with said two contacts whereby current will flow in one direction or the other in said winding when said contacts do not engage with points of equal potential on said two resistances, means controlled by said winding and responsive to the flow of current therein for moving said controlled contact to such position that said two contacts engage with points of equal potential on said two resistances, and governing apparatus on the vehicle controlled at least in part by the position of said controlled contact.

3. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, a motor having one winding constantly supplied with current and a second winding connected with said two contacts, means for moving said controlled contact by said motor, and governing apparatus on the vehicle controlled at least in part by the position of said controlled contact.

4. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, a motor for moving said controlled contact, means causing operation of said motor when said two contacts do not engage points of equal potential on said two resistances, and governing apparatus on the vehicle controlled at least in part by the position of said controlled contact.

5. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, a relay connected with said two contacts and responsive to the direction of current flow between said contacts, a motor controlled by said relay for moving said controlled contact, and governing apparatus on the vehicle controlled at least in part by the position of said controlled contact.

35 6. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, a relay having a winding connected with said two contacts and responsive to the direction of current flow in said winding, means controlled by said relay and operating when current flows therein to move said controlled contact to such position that the two contacts engage points of equal potential on said two resistances, and governing apparatus on the vehicle controlled at least in part by the position of said controlled contact.

7. In combination, a railway vehicle, a speed responsive device operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other

resistance, means connected with said contacts for keeping them at points of equal potential on said two resistances respectively, and governing apparatus on the vehicle controlled at least in part by the position of said controlled contact.

8. In combination, a railway vehicle, a speed responsive device thereon operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, means connected with said two contacts for keeping the controlled contact at a point on the second resistance having the same potential as the point at which the controlling contact engages the first resistance, a relay on the vehicle controlled in accordance with traffic conditions, and governing apparatus on the vehicle controlled jointly by said relay and by the position of said controlled contact.

9. In combination, a railway vehicle, a speed responsive device thereon operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, means connected with said two contacts for keeping the controlled contact at a point on the second resistance having the same potential as the point at which the controlling contact engages the first resistance, a relay on the vehicle controlled in accordance with traffic conditions, and governing apparatus on the vehicle controlled jointly by said relay and by the position of said controlled contact, and means controlled by said contacts for setting said governing apparatus into operation if the two contacts do not engage with points of equal potential on said resistances.

10. In combination, a railway vehicle, a speed responsive device thereon operatively connected with a wheel of said vehicle, two resistances on the vehicle each connected across a source of current, a controlling contact operated by said device and moved into engagement with different points on one resistance according to the speed of the vehicle, a controlled contact movable into engagement with different points on the other resistance, means connected with said two contacts for keeping the controlled contact at a point on the second resistance having the same potential as the point at which the controlling contact engages the first resist-

ance, governing apparatus on said vehicle controlled at least in part by the position of said controlled contact, and means for setting said governing apparatus into operation if said two contacts do not engage with points of equal potential on said resistances.

11. In combination, a railway vehicle, a speed responsive device operatively connected with a wheel of said vehicle, two impedances, means for applying an electromotive force to the terminals of each said impedance, a controlling contact operated by said device and moved into engagement with dif-

ferent points on one impedance according to the speed of the vehicle, a controlled contact movable into different points on the other impedance, means operating when said two contacts do not engage with points of equal potential on said impedances to move the controlled contact to such position that the two contacts do engage with points of equal potential on the two impedances, and governing apparatus on the vehicle controlled at least in part by the position of said controlled contact.

In testimony whereof I affix my signature.

CHARLES R. BEALL.
